CLAIM

The ornamental design for tapped detergent bottle, as shown and described.

DESCRIPTION

FIG. 1 is a top perspective view taken from a first embodiment of our new design for a tapped detergent bottle;
FIG. 2 is a front side elevation view of the first embodiment;
FIG. 3 is a rear side elevation view of the first embodiment;
FIG. 4 is a right side elevation view of the first embodiment;
FIG. 5 is a left side elevation view of the first embodiment;
FIG. 6 is a top plan view of the first embodiment; and,
FIG. 7 is a bottom plan view of the first embodiment;
FIG. 8 is a top perspective view taken from a second embodiment of our new design for a tapped detergent bottle;
FIG. 9 is a front side elevation view of the second embodiment;
FIG. 10 is a rear side elevation view of the second embodiment;
FIG. 11 is a right side elevation view of the second embodiment;
FIG. 12 is a left side elevation view of the second embodiment;
FIG. 13 is a top plan view of the second embodiment; and,
FIG. 14 is a bottom plan view of the second embodiment;
FIG. 15 is a top perspective view taken from a third embodiment of our new design for a tapped detergent bottle;
FIG. 16 is a front side elevation view of the third embodiment;
FIG. 17 is a rear side elevation view of the third embodiment;
FIG. 18 is a right side elevation view of the third embodiment;
FIG. 19 is a left side elevation view of the third embodiment;
FIG. 20 is a top plan view of the third embodiment; and,
FIG. 21 is a bottom plan view of the third embodiment.
The broken lines in the drawings illustrate the portions of the tapped detergent bottle that form no part of the claim.
